[57] CLAIM

The ornamental design for a skid member for caliper gauge contacting type, as shown and described.

DESCRIPTION

FIG. 1 is a top plan view of a skid member for a caliper gauge of contacting type showing my new design;

FIG. 2 is a right side elevational view, the left side elevational view being identical;

FIG. 3 is a bottom plan view; and

FIG. 4 is a cross-sectional view taken along line 4—4 of FIG. 3 thereof.

FIG. 1.

FIG. 2.

FIG. 4.
